UNITED STATES PATENT OFFICE

105,174

DESIGN FOR A RADIO DIAL ESCUTCHEON PLATE

Mahlon W. Kenney, River Forest, Ill., and George W. Walker, Pleasant Ridge, Mich., assignors to General Household Utilities Company, Chicago, Ill., a corporation of Delaware

Application November 11, 1936, Serial No. 65,854

Term of patent 7 years

To all whom it may concern:

Be it known that we, Mahlon W. Kenney and George W. Walker, citizens of the United States, residing at River Forest, Cook County, Illinois, and Pleasant Ridge, Oakland County, Michigan, respectively, have invented a new, original, and ornamental Design for a Radio Dial Escutcheon Plate, of which the following is a specification, reference being had to the accompanying drawing, forming a part thereof.

Figure 1 is a front elevational view of the radio dial escutcheon plate showing our new design.

Figure 2 is a top plan view of the escutcheon plate shown in Figure 1.

We claim:

The ornamental design for a radio dial escutcheon plate as shown.

MAHLON W. KENNEY.
GEORGE WM. WALKER.
